CHAIR

Arthur C. Ferro, Creve Coeur, Mo., assignor to Contour Chair-Lounge Co., Inc., St. Louis, Mo., a corporation of Missouri

Filed July 26, 1965, Ser. No. 86,288

Term of patent 14 years

(Cl. D15—11)

The side of the chair not shown is a mirror image of the side shown.

I claim:

The ornamental design for a chair, as shown and described.
